AUTOMOBILE ASH TRAY

Robert E. Hammond, Dayton, Ohio

Application June 18, 1956, Serial No. 41,947

Term of patent 14 years

(Cl. D85—2)

FIG. 1

FIG. 2

FIG. 3

FIG. 4

FIG. 5

FIG. 6

FIG. 7

FIG. 8

Fig. 1 is a perspective view of an automobile ash tray in mounted disposing position showing my new design, with the broken line automobile window being shown for illustrative purposes;

Fig. 2 is a top plan view of Fig. 1;

Fig. 3 is a top plan view in closed, non-disposing position;

Fig. 4 is a front elevational view of Fig. 2;

Fig. 5 is a rear elevational view of Fig. 2;

Fig. 6 is a left end elevational view of Fig. 2;

Fig. 7 is a right end elevational view of Fig. 2; and

Fig. 8 is a bottom plan view of Fig. 2.

I claim:

The ornamental design for an automobile ash tray, substantially as shown and described.
